UNITED STATES PATENT OFFICE.

JOHN W. ROHM, OF PITTSBURG, PENNSYLVANIA.

DESIGN FOR A LAMP OR TORCH BODY.

SPECIFICATION forming part of Design No. 18,669, dated October 2, 1888.

Application filed August 1, 1888. Serial No. 281,694. Term of patent 7 years.

To all whom it may concern:

Be it known that I, JOHN W. ROHM, a citizen of the United States, residing at Pittsburg, in the county of Allegheny and State of Pennsylvania, have invented and produced a new and original Design for a Lamp or Torch Body; and I do hereby declare the following to be a full, clear, and exact description of the same, reference being had to the accompanying drawing, forming a part thereof, which represents a view of the torch-body illustrating my design.

My design consists, generally stated, in a lamp or torch body having the shape or form of a canoe.

In the accompanying drawing my design is illustrated in connection with a torch-body, the body *a* of the torch being the shape of a canoe and the top portion being closed by a cover, *b*, and having leading up from the cen-

ter thereof the burner *c*, which in the accompanying drawing is illustrated as an ordinary torch-burner. The torch-body is shown as hung from the arms *f*, which are secured to the top of the handle *g*, the canoe-shaped body ²⁵ of the torch being hung at the upper ends of the canoe-body from the ends of the arms *f*.

What I claim as my invention, and desire to secure by Letters Patent, is—

The design for a lamp or torch body herein ³⁰ shown and described, the same consisting of the lamp or torch body having the shape of a canoe and provided with a burner, substantially as set forth.

In testimony whereof I affix my signature in ³⁵ presence of two witnesses.

JOHN W. ROHM.
